United States Patent

Des. 235,543
Patented June 24, 1975

235,543

AIRCRAFT-BORNE SPRAY UNIT

Richard Werling, Fort Atkinson, and James P. Lindsey,
Janesville, Wis., assignors to Omnipilot Helicopters,
Inc., Janesville, Wis.

Filed May 17, 1973, Ser. No. 361,263

Term of patent 14 years

Int. Cl. D23—01

U.S. Cl. D23—18

FIG. 1

FIG. 4

FIG. 5

FIG. 1 is a side elevational view of an aircraft-borne spray unit showing our new design;

FIG. 2 is a top plan view thereof;

FIG. 3 is a front elevational view thereof;

FIG. 4 is a rear elevational view thereof; and

FIG. 5 is a bottom plan view thereof.

We claim:

The ornamental design for an aircraft-borne spray unit, as shown.
